9 Claims. (Cl. 175—329)

This invention relates to rotary diamond drill bits of the type having abrasive areas in which diamonds are embedded, and having an outlet passage for drilling fluid.

In most known rotary drill bits of this general type the drilling fluid is passed axially into the bits and is then divided into a plurality of secondary jets in an end portion of the bit, so that the fluid assumes in each of such secondary jets a radial velocity component within the flow passage defined by the bit outlet and the bottom of the drill hole being excavated. This radial velocity interferes with the proper flow of fluid across the abrasive areas of the bit so that the diamonds are not kept in the clean, mud-free condition in which they will develop their optimum cutting action.

It is an object of this invention to provide an improved diamond drill bit in which the above and other defects of prior diamond drill bits associated with the flow of drilling fluid are obviated. An object is to provide a diamond drill bit in which the drilling effectiveness is enhanced and maintenance problems reduced through a more effective design and cooperation of the abrasive surfaces and the drilling fluid flow passages.

Other objects will appear.

Exemplary embodiments of the invention will be described with reference to FIGS. 4-11 of the accompanying drawings given for purposes of illustration but not of limitation. In the drawings:

FIGS. 1-3 relate to a conventional form of diamond drill bit, FIG. 1 being a bottom plan view thereof, FIG. 2 a section on line II—II and FIG. 3 a section on line III—III;

FIG. 4 is an idealized perspective view of the vein of drilling fluid present within the cavities of an improved diamond drill bit according to a form of the invention;

FIG. 5 is a bottom plan view of an improved drill bit according to the form of the invention shown in FIG. 4;

FIGS. 6 and 7 are elevational views thereof on two mutually normal planes;

FIG. 8 is a bottom plan view of drill bit according to another form of embodiment of the invention;

FIG. 9 is a similar view in yet another modified embodiment;

FIG. 10 is a side view of a ribbed or fluted drill bit according to a further modification, and

FIG. 11 is an idealized perspective view analogous to FIG. 4 showing the shape of the drilling fluid vein present in the cavities of another form of drill bit according to the invention.

Some of the shortcomings of conventional drill bits will first be briefly described with reference to FIGS. 1-3, which illustrates a typical diamond drill bit of a widely used type which need not be described in detail, beyond saying that the bit includes three generally helicoidal abrasive areas 5 which are studded with diamonds, and between which three helicoidal grooves 3 are defined, which constitute outlet channels for drilling liquid delivered into and through the bit by means not shown. FIG. 1 shows a vector diagram of the flow velocities of the fluid in an outlet groove 3. It will be noted that there is a radial velocity component V1 of the fluid with respect to the bottom of the hole being drilled. The vector V2 indicates the relative linear velocity of rotation of the

2

drill-hole bottom with respect to the bit, and the vector V3 is the resultant velocity of the fluid with respect to the bit.

As shown in FIG. 2, the drilling fluid is delivered as indicated by arrow 1 into an axial passage of the drill bit. It is noted that FIG. 2 is only a half view, showing the borehole and drill bit on one side of the center axis 2. The arrows 4 indicate the flow velocity of the fluid through an outlet channel or groove. The sectional view of FIG. 3 serves merely to illustrate the flow passage for drilling fluid which is defined between the bottom of a groove 3 on one side, and the surface 6 of the well being drilled on the other.

The type of drilling fluid flow thus provided in conventional diamond drill bits of which the one illustrated in FIGS. 1-3 is a typical example has several serious drawbacks. Thus, the flow section of the passages usually diverges, so that the flow velocity decreases. Moreover, the fluid flowpath includes a portion in which the flow velocity is parallel to the bottom of the well, as will be particularly clear from FIG. 2. Moreover throughout the flowpath the fluid is channeled in the outlet grooves, so that it is prevented from streaming across the diamond-studded cutting areas 5 of the drill bit; such streaming however would be extremely desirable in that it would provide a much more efficient washing action preventing the accumulation of mud which otherwise plugs the diamonds and limits their cutting action. Objects of this invention are to eliminate these difficulties.

According to an aspect of the invention, a drill bit comprises at least two component parts provided with diamond-studded abrasive areas, said parts being separated by an intermediate cavity of relatively narrow width dimension and of generally flat rectangular (or slot-like) shape, the midplane of which coincides with a diametric or radial plane of symmetry of the drill bit, and means are provided for injecting the drilling fluid from an axial inlet passage into said cavity. It will be appreciated that with such an arrangement the drilling fluid, rather than being subdivided into a plurality of comparatively ineffective minor streams retains its full dynamic impetus or jet effect throughout its flowpath through the tool and the total variation of momentum to which the fluid stream is subjected is made to occur over a considerably smaller area of ground, than is the case in conventional drill bits, so that its cleaning or flushing action gains considerably in effectiveness. Moreover as will presently appear a streaming of the fluid across the abrasive surfaces of the bit is produced thereby improving the sustained cutting ability of the diamonds imbedded in said surfaces.

The above features will be more clearly apparent from a consideration of FIG. 4 which intends to illustrate the form of the liquid vein present within the internal cavities of an improved drill bit, the actual solid portions of which are not shown. Thus the portion 7 of the fluid vein is that flowing through the axial delivery or inlet passage of the drill bit. As the fluid issues from this inlet passage it is pinched or laminated within the flat cavity defined between the two parts of the bit as earlier stated, thereby constituting a narrow, high-velocity sheet of fluid having increased effectiveness, in contrast with the several jets into which the fluid vein divides in conventional drill bits of the kind first described.

It may here be noted that in certain types of diamond drill bits of the prior art the drill bit has been provided with a narrow slot-like cavity along a diametrically extending plane thereof, into which the drilling fluid was injected. However in prior drill bits of that type the cavity separating the abrasive elements of the drill included flared outer portions towards the side edges of the end of the drill bit, thereby greatly reducing the jet effect developed by the fluid vein. Moreover the bit was so

shaped that the fluid flowpath included a section directed outward and upward of the drill bit, so that the tangential velocity effect of the jet was all but completely suppressed. In contrast, the flat separating cavity of the drill bit of my invention is so designed that the jet effect of the fluid is retained throughout the entire flowpath, and so that the impact angle of the fluid jet against the bottom wall of the well being drilled approximates 90°. Further, the vane-like shape of each abrasive element in the improved drill bit, as will presently appear, results in increasing the pressure differentials across each abrasive area, thereby improving the effectiveness of the washing or flushing action.

Thus, returning to FIG. 4, it will be noted that the flow velocity of the drilling fluid is axially directed, i.e. is parallel to the axis of the drill hole, and retains such axial direction up to the point of impact of the fluid against the bottom of the hole. True this purely axial flow condition tends to be disturbed by the action of centrifugal forces set up by the rotation of the drill. However, this adverse effect can and preferably is disposed with, according to the invention, as by providing rectifier baffle means, e.g. as shown at 9 and 10 within the cavity (FIGS. 5, 6 and 7), which will act to restore the axial flow of the fluid.

Thus, referring again to FIG. 4, it will be noted that the flow velocity of the drilling fluid is, all along the outer edge of the slot 17, directed perpendicularly to the wall of the hole. However the main part of the flow must be axially directed; i.e., parallel to the axis of the drill hole and this condition tends to be disturbed by the action of centrifugal forces set up by the rotation of the drill. Such an adverse effect can be, and is preferably controlled, according to the invention, by providing rectifier baffle means; e.g., as shown at 9 and 10 within the cavity, which will act to restore the axial flow of the fluid.

Reference will now be made to FIGS. 5-7 which illustrate the actual construction of one form of drill bit according to the invention. The drill bit comprises a bit stock 11 formed with an axial bore 12 through it for the delivery of the drilling fluid, and provided at its top with a tapered threaded section 13 for connection with a drill shank. The bit further includes a generally semi-oval drill head 14 which is divided by a generally diametric cut or slot 17 into two spaced elements 15 and 16. It will be appreciated that it is the slot 17 in the drill bit shown in FIGS. 5-7 which provides the flat vein of fluid referred to previously and designated 8 in FIG. 4. The ends of the spaced elements 15 and 16 are tapered inwardly in the manner shown in dotted lines 17a in FIGS. 6 and 7 to provide a relatively flat conical concavity 17b in the end of the drill bit.

According to an advantageous feature in this form of the invention, each of the bit elements 15 and 16 is provided with an abrasive area on only one-half of its cutting edges. The element 15 has a diamond-studded abrasive area only in the half-portion 18 of its edge surface whereas the half-portion 19 has none; similarly element 16 has an abrasive area on the portion 20 of its edge surface while portion 21 is smooth.

The smooth portions 19 and 21 of the respective bit elements 15 and 16 are displaced or offset upwardly from the related abrasive portions 18 and 20, as will be clear from FIG. 7. It will also be noted from FIGS. 6 and 7 that the cutting areas are shaped stepwise. Considering for instance cutting area 18 of element 15, there is a lowermost contour line 22 (also see FIG. 5) from either side of which the adjacent contour lines are positioned at higher elevations over the surface of area 18, the three steps spaced radially inwardly of contour 22 thus defining a segment of an axial cavity in the bottom surface of the bit. The other segments thereof are provided by the corresponding steps on abrasive portion 20 and by the respective adjacent indentation on those extremities of

smooth portions 19 and 21 which are nearest the bit axis. The same configuration applies to cutting area 20.

A pair of diametrically opposed stabilizer projections 23 and 24 are provided on the upper end of the bit stock 11 for centering and guiding the bit in its rotation, the projections 23 and 24 being adapted to engage the sides of the drill hole and consequently being diamond-studded. Preferably moreover a pair of opposite tapered projections 25 and 26 are provided on the inwardly directed facing surfaces of the two elements 15 and 16, so as to reduce the size of the core that tends to form inside the gap or slot 17. Any small core that does form is quickly broken up by the jet of drilling fluid discharged through said slot.

As shown in FIG. 5, the drill bit is adapted in operation to be rotated in the direction indicated by arrow 27. Hence, referring to this direction of rotation, it will be observed that the abrasive area 18 of element 15 is disposed on the trailing side from the slot 17 and the upwardly offset smooth area 21 of the other element 16 is disposed on the leading side from slot 17. Similarly abrasive area 20 is on the trailing side of the slot while the upwardly displaced smooth area 19 is on the leading side of the slot. The smooth area 19, 21 of each element of the bit should be upwardly offset a minimum amount so as not substantially to engage the bottom of the drill hole (since it is not fitted with diamonds) while still being capable of limiting or preventing the leakage of drilling fluid in the forward direction of rotation of the bit.

In the operation of the drill bit just described, the drilling fluid discharged in a fast solid jet of a flat sheet-like configuration through slot 17 strikes the bottom of the drill hole with maximum force. As earlier noted and as indicated by the vector diagram in FIG. 7, the radial velocity component of the fluid is substantially zero, while it is flowing through the bit. The fluid flow velocity has this characteristic because the narrow slot width prevents the fluid from attaining any substantial velocity perpendicular to the midplane of the slot while the tendency of the fluid to flow in a radial direction parallel to said midplane is counteracted by the inwardly directed radial velocity components induced by baffles 9 and 10. On striking the bottom of the well the fluid is deflected tangentially as indicated by vector V2 and assumes the resultant velocity relative to the bit indicated by vector V3, which drives it under and across the trailing abrasive surface on each side of the bit. It will be appreciated that for a given discharge rate V1 of the fluid the effectiveness of the flushing action of the fluid on the abrasive surfaces will be the greater as the velocity ratio V2/V1 is greater, and hence as the angular rate of bit rotation is higher.

The velocity diagram indicated achieves a dual beneficial effect. In the first place the fluid, on striking the bottom of the well, is subjected to a variation in its momentum which is very high (jet effect) and thus exerts a maximum flushing effect against the well bottom. Thereafter the fluid on being deflected tangentially exerts a similar effective flushing action on the cutting area of the bit. It will be appreciated that the width dimension of the slot 17 should be so predetermined as to provide an optimum value for the axial discharge velocity V1 and a tangential velocity V2 consistent with the abrasion resistance of the bit surfaces in which the diamonds are imbedded. Flow velocities in a range of 60 meters per second are generally found suitable. It is important to note that since, according to the invention, the drilling fluid is released from the bit an extremely short distance from the bottom of the well, the flow velocities used may if desired be selected at substantially lower values than in conventional bits. The distance at which the jet is released from the bit is only a few millimeters from the bottom of the well, i.e. a distance corresponding to the projecting length of the diamonds.

It will be understood that the contours of the bit shown

in FIGS. 5 to 8 may be varied considerably without departing from the teachings of the invention. The contours selected by way of example are typical of those widely used at present.

In the modified embodiment shown in FIG. 8, the general construction is the same as described for the first embodiment, the only difference being the fact that the two elements 28 and 29 of the bit, separated by the gap or slot 30 according to the invention, include abrasive cutting areas 31 and 32 which are of generally triangular form, tapering toward the end of the bit.

In the further modification of FIG. 9, the arrangement differs from those heretofore shown in that both elements 33 and 34 of the bit, separated by the gap 35, are fitted with diamonds throughout their end surfaces, there being no offset smooth areas as in the first embodiment disclosed. Such a bit may prove advantageous in that the drilling fluid discharged through slot 35 will have less tendency to escape by leakage past the end surface of the bit element positioned in front of the gap in the direction of rotation. The flushing effect is thereby further improved. However, a drill bit of the type shown in FIG. 9 is obviously more expensive both to construct, owing to the greater amount of diamond material required, and to operate, since more hydraulic power must be applied to offset the increase in the total pressure loss sustained by the drilling fluid across the end surfaces of the bit.

As already noted, the effectiveness of the flushing action increases as the rate of bit rotation is increased. However, in case of an excessively high rotational velocity, the centrifugal force acting on the body of the drilling fluid contained in the central slot of the bit tends to throw the fluid outwards and the washing effectiveness in the central parts of the cutting areas may then be decreased. As earlier indicated, this may be remedied by the provision of rectifier blades 9 and 10 (FIGS. 5 and 6) within the slot. Alternatively, the cross sectional shape of the slot in a plane normal to the drilling axis may be modified as by increasing its width dimension toward the center of the bit.

In the modification shown in FIG. 10, the general construction of the drill bit is similar to that shown in FIGS. 5-7. It additionally includes a pair of longitudinal flanges or ribs 36 and 37 projecting normally from the elements 15 and 16. These flanges or ribs serve to oppose equalization of the pressures obtaining on opposite sides of the oppositely disposed elements of the bit. That is, it may be observed that the drill bit of the invention can be compared to a revolving vane in which an excess pressure tends to build up ahead of the end of each element of the drill bit in the direction of drill rotation and a corresponding pressure drop to the rear thereof. The resulting pressure differentials tend to increase the rate of flow of the drilling fluid past the abrasive areas and hence the effectiveness of the diamond-flushing action. Normally however these pressure differentials may be cancelled by the establishment of a flow of fluid across each outerface of the bit. This undesirable pressure-equalizing-effect is opposed by the provision of the flanges or ribs 36 and 37 in that the same subdivide the area defined on the outer side of each element 15, 16 thereby opposing the equalization of pressure on said side of each element and correspondingly enhancing the pressure differentials noted.

In all of the embodiments of the invention heretofore described, the drill bit was provided with a single diametrically extending slot or gap between two parallel spaced bit elements. However, the number of bit elements is not necessarily limited to two. Thus there may be provided three bit elements separated from one another by three circumferentially equispaced slots or gaps through which the drilling fluid is discharged. FIG. 11 illustrates the appearance of the fluid vein present in the cavities of

a drill bit thus constructed. It is believed that in the light of the explanations already given, the construction of a drill bit according to the invention wherein the cavity configuration will be substantially that shown in FIG. 11 can readily be inferred by those familiar with the art so that further detailed description of such embodiment would be superfluous.

What I claim is:

1. A rotary drill bit comprising stock means adapted to be attached to the lower end of a drill pipe and provided with a generally axial passage for the delivery of the drilling fluid and a head means secured to said stock means, said head means being constituted by at least two portions extending longitudinally of the axis of said drill pipe, each of said portions having at least one abrasive area on an outer surface of said head means and at least one surface defining a respective wall of a slot, extending at least from said axis, to the outer surface of said head, said walls being symmetrically disposed on opposed sides of a plane passing through said axis and being shaped so that, along at least a portion of said axis, the width of said slot, at any point in a plane perpendicular to said axial plane, is not greater than its width at said axis.
2. A bit as recited in claim 1 wherein only two of said portions are employed, each defining substantially one-half of said head means, and wherein said slot extends entirely across a diameter of said head.
3. A bit as recited in claim 1, wherein along at least a portion of the axial extent of said head, said surfaces defining respective walls of said slot are flat over the entire radial extent of said head.
4. A bit as recited in claim 1 wherein said surfaces defining respective walls of said slot converge in a radial direction from said axis to the periphery of said head along at least a portion of the axial extent of said head.
5. A bit as recited in claim 1 wherein each of said portions also has a smooth area displaced axially away from the bottom of said bit with respect to said abrasive area.
6. A bit as recited in claim 1 wherein each of said portions extending longitudinally of said drill pipe includes a tapered projection extending into said slot from said surface defining a respective wall of said slot.
7. A drill bit as recited in claim 1 further comprising baffle means mounted in said slot for deflecting said drilling fluid towards said axis in a direction parallel to said axial plane.
8. A drill bit as recited in claim 1 wherein each of said portions comprises, on an outer surface thereof, at least one longitudinal rib for engagement with the sides of a drillhole to oppose equalization of the differential pressures set up across the surfaces of said portions during drill rotation.
9. A drill bit as recited in claim 1 further comprising: at least two stabilizer projections on said stock means for engagement with side walls of the drill hole; and abrasive means mounted on the engaging end surfaces of said projections.
